UNITED STATES PATENT OFFICE.

ISAAC D. SMEAD, OF CINCINNATI, OHIO.

GARBAGE-CREMATORIUM.

No. 872,466.

Specification of Letters Patent.

Patented Dec. 3, 1907.

Application filed January 5, 1906. Serial No. 294,741.

To all whom it may concern:

Be it known that I, ISAAC D. SMEAD, a citizen of the United States, residing at Cincinnati, in the county of Hamilton and State of Ohio, have invented certain new and useful Improvements in Garbage-Crematories, of which the following is a specification.

My present invention relates to garbage crematories, the construction and advantages of which will be hereinafter set forth, reference being had to the annexed drawings, wherein:

Figure 1 is a longitudinal sectional view of the apparatus; Fig. 2 a side elevation of the rear portion thereof; Fig. 3 a transverse vertical sectional view, the left-hand portion being taken on the line 3—3 and that portion to the right on the line 3^a—3^a of Fig. 2. Fig. 4 a detail sectional view of the crushing-rolls and belt; Fig. 5 a perspective view of a portion of one of the cross-bars of the belt and its attached links; and Fig. 6 a longitudinal sectional view of a portion of the lower crushing-roll, one of the cross-bars, and the attached links.

The main object of the invention is to provide means for positively feeding the garbage between the crushing and expressing rolls and to thereafter deliver the same into the retort.

A further object is to provide means for introducing fuel into the retort with the garbage, and to utilize the same conveyer for carrying the fuel and garbage.

A still further object is to provide means for preventing too great a draft from passing into the apparatus when the garbage-hopper is opened for the reception of a fresh charge of material.

With these and other objects in view I will now describe the invention.

In the main the invention embodies certain features of the construction set forth and claimed in Letters Patent No. 794,471, granted to me under date of July 11, 1905; that is to say, two retorts, designated by the letters A and B, are employed, said retorts being located in the lower portion of the main body of the structure and communicating with the two stacks C and D, stack C affording a direct draft, while stack D gives an indirect draft and causes the products of

combustion to pass through the fire-tubes of the boiler E. A suitable blower, as in the former construction, will be employed, the air from said blower passing through a pipe F and being discharged beneath the grates of the retorts in the manner best shown in Fig. 1.

The garbage or the like which is to be cremated is placed from time to time in a hopper G, which is provided with a swinging cover H. The hopper, as will be seen upon reference to Fig. 1, is provided with an inclined bottom I, which terminates at a point just above the conveyer-belt, the construction of which will be hereinafter set forth in detail. The forward portion of the hopper is provided with a swinging apron J, which extends downwardly toward the conveyer and terminates at a point slightly above the pipe K through which steam is introduced for the purpose of heating the garbage when occasion requires. The swinging apron J prevents too great a draft from passing in through the hopper when the cover is opened and there is but relatively little garbage in the hopper. The conveyer is composed of a series of bars L, which are secured to lugs or ears M that extend outwardly from the chain-links N (Fig. 5). As will be seen upon reference to Fig. 6, there are two chains composed of a series of links, as N, the bars being secured at each end to said chains.

The upper crushing-roll, O, is fluted and extends across the entire width of the chamber P (Fig. 1), and the lower crushing-roll, Q, also extends across the entire width of said chamber. The lower crushing-roll Q is of the form best shown in Figs. 4 and 6, the roll being provided with a series of teeth or ribs R which pass up between the cross-bars L of the conveyer-belt. Each end of the roll Q is provided with a flat surface S upon which the links of the chains rest, the ribs R, as before mentioned, passing in between the adjacent cross-bars L of the belt.

As will be noted upon reference to Fig. 4, the upper crushing-roll stands directly above the lower crushing-roll, and inasmuch as the ribs or teeth R of the lower roll pass up through the openings between the cross-bars L the garbage cannot be forced through the belt, although the expressed liquid may find a free passage therethrough.

Adjacent to the opening formed between the retort B and the chamber P is mounted a roller T, provided with a series of ribs or teeth which extend lengthwise thereof and pass into the openings between the bars L. Said roller T is driven by means of a worm-wheel U, worm V and an engine or motor W, the latter, by suitable gearing, imparting motion to the worm, see Fig. 2. This roller 10 T forms in effect the driving member for the conveyer-belt, and the ribs thereon, by reason of passing into the spaces between the cross-bars L of the conveyer, expel any garbage which may have been forced into the 15 same by the action of the crushing-rolls O and Q. The conveyer or belt at its lower end passes about an idler-roll X. Inasmuch as the ribs R of the lower roll Q are always in mesh with the belt or conveyer, said roll is 20 driven thereby, and through the gears Y and Z (Fig. 2) positive rotary motion is imparted to the upper crushing-roll O. By the employment of a conveyer or belt thus constructed the garbage is positively fed in between the crushing-rolls so that all hard substances are broken, and the moisture (to a considerable extent) is expelled from the 25 garbage and passes down into the liquid-receptacle A' located in the lower portion of 30 the chamber P. If the garbage is greasy it will not pass between the two rollers, either plain or fluted, but by the employment of the conveyer-belt the garbage is taken from the hopper and positively passed between the 35 crushing-rolls, and from these rolls is discharged into the retort B, where it is consumed.

Located above the chamber P is a fuel-receptacle B', provided with an opening C' 40 the size of which is regulated by a sliding door or valve D'. In practice it is found desirable to mix a certain amount of fuel with the garbage as it is carried forward to the retort B, and by regulating the size of the 45 opening C' the amount of fuel fed into the retort with the garbage may be regulated as desired. Furthermore, the belt may be used as a fuel-conveyer, *per se*.

Inasmuch as the garbage is usually collected from a series of small receptacles, 50 some means should be provided for removing the grease from the interior thereof, and to this end I have provided a pipe E' (Fig. 2) connected with the steam-space of the boiler, 55 and through which steam may be directed to the interior of the receptacles from which the garbage is collected. The adhering grease will thus be melted and may be emptied into the hopper.

60 In order to prevent the escape of any fumes or odors from the chamber P through the opening C' or through hopper G, I provide a flue or opening F' (Fig. 1) which ex-

tends from the upper portion of the chamber P into the fire-space G' of the boiler. This 65 opening is of such size as not to materially affect the draft through the fire-tubes, but is sufficient to cause an upward draft from the chamber P, as indicated by the arrows in Fig. 1.

70 While I have shown the invention as applied to a portable crematory, it is to be understood, of course, that it is equally applicable to a stationary plant, and the claims are not to be restricted to either form of apparatus.

Having thus described my invention, what I claim is:

1. In a crematory, the combination of a retort; a hopper for the reception of garbage or the like; a conveyer extending from the hopper and discharging into the retort, said conveyer comprising two endless chains and a series of cross-bars connected to said chains; a fluted crushing-roll located above 85 said conveyer; a second crushing-roll situated below said conveyer, the lower roll being provided with a series of teeth extending lengthwise thereof and likewise having a flat surface at each end upon which the chains 90 may rest; and means for driving said conveyer.

2. In a crematory, the combination of a retort; a hopper for the reception of garbage or the like; a conveyer comprising a pair of 95 chains with a series of cross-bars connected at their ends to said chains; a driving roll for said conveyer, said roll having a series of teeth extending longitudinally thereof and arranged to pass inwardly between the cross-bars; a fluted crushing-roll located above 100 the conveyer; a second crushing-roll situated below the upper stretch of the conveyer, said second crushing-roll being provided with a series of teeth which extend throughout the 105 length thereof and with a flat surface at each end upon which the chains of the conveyer may rest; and driving connections between said crushing-rolls.

3. In a crematory, the combination of a 110 retort; a hopper for the reception of garbage or the like; a conveyer extending from said hopper and discharging into the retort, said conveyer comprising a series of separated bars extending crosswise thereof; a pair of 115 crushing-rolls acting in conjunction with said conveyer; and a third roll located at a point adjacent to the retort and serving to force the material from between the cross-bars of the conveyer and to thereby discharge it into the retort, substantially as described.

4. In a crematory or the like, the combination of a retort; a boiler located above the same; a chamber situated at a point in rear 125 of the retort; a hopper for the reception of

garbage located at the outer end of said chamber; means contained within said chamber for crushing the garbage and delivering the same to the retort; and a flue or opening extending from the upper portion of the chamber, said flue opening into the stack of the boiler, substantially as and for the purpose described

In testimony whereof I have signed my name to this specification in the presence of 10 two subscribing witnesses.
